Attest:

UNITED STATES PATENT OFFICE

REINHARD E. BARTELS, OF LYNN, MASSACHUSETTS; IDA M. BARTELS AND R. BUR-
LEIGH BARTELS EXECUTORS OF SAID REINHARD E. BARTELS, DECEASED

METHOD OF REPAIRING SHOES

Application filed November 20, 1925. Serial No. 70,343.

This invention relates to a method of repairing shoes and more especially shoes wherein the shank stiffener has become broken through usage or otherwise, or is of insufficient strength or is otherwise faulty. Ordinarily in repairing such shoes, the broken or weak stiffener is removed and a new stiffener substituted therefor. In welt and McKay shoes, the stiffener is located at the shank, between the inner and outer soles, and the removal of the stiffener would necessitate certain parts of the shoe to be ripped apart. In a turn shoe, the stiffener is positioned on the inside of the sole.

The object of the present invention is to provide a method whereby a shoe in which a shank stiffener has become broken or is weak may be repaired without necessitating the ripping apart of the shoe. Briefly stated, this object is attained by superimposing a unit comprising a new stiffener within the shoe and fixing it in place.

With the foregoing and other objects and advantageous features in view, a more complete understanding of the present invention may be gained from the following detailed description thereof when considered in conjunction with the accompanying drawings, in which—

Figure 1 represents in detail perspective a one-piece metal shank stiffener which may be employed in the present invention.

Figure 2 is a similar view representing a shank piece with which it may be assembled to form a stiffener unit.

Figure 3 shows a two-piece stiffener which may be used.

Figure 4 represents, in plan view, the stiffener assembled with the shank piece and prepared to be superimposed as a unit and fixed in place over the old stiffener.

Figure 5 illustrates a turn shoe partly in section, in which a new stiffener has been attached in place in accordance with the present invention.

Figure 6 illustrates a welt shoe, partly in section, wherein a stiffener is broken.

Figure 7 is a similar view to Figure 6, showing a new unit secured in place.

Figure 8 represents a section on the line 50 8—8 of Figure 7.

Referring to the drawings, in Figure 1, 1 represents as a whole a one-piece stiffener of any suitable form, which may be employed in connection with the method of the present invention. The stiffener shown consists of a suitably formed strip of metal provided with prongs 2 struck out upwardly therefrom, adjacent to its ends, and by means of which it may be fastened or clinched to the shank piece 3 illustrated in Figure 2, which is cut to overlie the shank and the heel of the shoe.

In place of the stiffener shown in Figure 1, one may, for instance, employ a two-piece construction, as illustrated in Figure 3, which consists of the upper strip 5, provided with the prongs 6 struck up therefrom adjacent to its ends, by means of which it may be secured to the shank piece 3, and a lower strip 7 of suitable form, spot-welded or otherwise united therewith. Any other suitable type of stiffener may be used, if desired, the ones shown and described being by the way of illustration only.

After the stiffener has been assembled with the shank piece, as illustrated in Figure 4 to form a completed stiffener unit S, a hole h is drilled or otherwise suitable formed at the desired location in the unit, so as to extend completely through the shank piece and stiffener. One or more holes, P and i, are also formed adjacent to the heel portion of the shank piece 3 and adjacent to the forward end, preparatory to the placement of the unit S over the broken unit and its securement in position.

In applying the unit S to the shoe M illustrated in Figure 5, the lining L overlying the faulty stiffener is raised so that the new unit may be superposed over the similar old, 90

broken, or weak unit B. Tacks T are then inserted through the holes P and driven through the shank piece of the old unit and through the heel *e* of the shoe. Similarly, 5 tacks T are inserted through the holes *i* and driven through the sole portion of the old shank piece and through the sole *f* of the shoe. A tack T is also inserted through the hole *h*, which extends through the shank piece and 10 stiffener of the unit S, and is driven through the shank piece *r* of the old unit. In driving the tack, the end thereof is forced against the metal stiffener N of the old unit and clinched thereon in the shank piece *r* so that 15 the shank parts are fixed to the stiffener unit. After the securement of the new stiffener unit, the lining may be laid thereover and suitably fixed in position as previously.

It is of course obvious that a greater number 20 of holes may be formed through the shank piece and shank stiffener, so that a greater number of stopping or engaging elements for clinching the old stiffener to the new stiffener may be had, but under ordinary circumstances it has been found that one engaging element is sufficient to maintain the new stiffener in position.

In Figure 6, I have illustrated a welt shoe W, wherein the metal stiffener 15, which is 30 located between the inner sole 16 and the outer sole 17, is weak or broken. In applying a new stiffener unit S thereto, the unit is placed over the inner sole and secured in place by inserting tacks through the several holes indicated, and driving them into the shoe, and then, if desired, a sock lining L' is placed 35 over it. The tack inserted into the opening *h* is thus driven into the inner sole 16 and is clinched on the metal strip 15 as indicated. 40 The tacks inserted into the holes P are driven through the inner and outer soles into the heel *e*, and those inserted into the holes *i* are driven through the inner sole and into the outer sole. Similarly, also, in a McKay shoe, 45 the repair unit would be placed on the inner sole and the central nail clinched on the old stiffener positioned between the inner and outer soles.

By the method described, a durable and efficient repair of the shoe is effected with a 50 minimum amount of effort and in a minimum period of time, since the necessity of removing any parts has been done away with.

Having thus described this invention, it 55 should be obvious that various changes or modifications might be resorted to in the procedure, as well as in the construction of the various parts, without departing from the spirit or scope of the invention as defined 60 by the appended claim.

I claim:

A method of repairing shoes wherein the shank stiffener is faulty, which comprises forming a hole through the shank piece and 65 stiffener of a stiffener unit at the desired lo-

cation, superimposing the unit above the old stiffener, tacking it to the shoe near its ends, and inserting a tack through said hole formed through said unit and driving said tack in a manner to cause the end of said tack to be clinched against a portion of said old stiffener.

In testimony whereof I have affixed my signature.

REINHARD E. BARTELS.
